UNITED STATES PATENT OFFICE.

IVA CADIEUX, OF LONG BEACH, CALIFORNIA.

COMBINATION GARMENT.

Application filed May 29, 1924. Serial No. 716,568.

To all whom it may concern:

Be it known that I, IVA CADIEUX, a citizen of the United States, residing at the city of Long Beach, in the county of Los Angeles, State of California, have invented new and useful Improvements in Combination Garments, the Same Being Composed of a Brassière and Chemise, of which the following is a specification.

10 The object of my invention is to provide a single combination garment which performs the functions of two garments usually made separable and handled separately, thereby saving time and material in the making of 15 the garments and saving time in putting on and taking off the combined garment over that required in making or putting on and taking off two separate garments.

In the drawings forming a part of this 20 application Fig. 1 is a front view of my combined garment. Fig. 2 is an enlarged detail showing a fragment of the back.

Referring to the drawings, 5 is the skirt and 6 the waist of a chemise of my improved 25 garment which is cut to fit the wearer. A brassière 7 of suitable cut is connected at the top to the top of the waist of the chemise, thereby making the top finishing seam the finishing seam for both garments. I provide an opening shown in Fig. 2 by full 30 lines at 8 as being in the back of the garment, but it is obvious that the opening could be in the front of the garment. The opening in the brassière extends from the top to the 35 bottom and the opening in the chemise extends from the top to a suitable distance in the skirt. The opening in the brassière is provided with suitable fastening means, illustrated as hooks 9 at one side and eyes 10 at the other side. Below the brassière the opening in the chemise is provided with like 40 fastening means. Shoulder straps 11 com-

plete the garment. It will be observed that the top hook and eye fastens the top of the brassière and the chemise and the fastening 45 of the remaining fasteners of the brassière causes the closing of the waist of the chemise and the fastening of the lower fasteners of the chemise completes the fastening of the garment on the wearer. The wearer after 50 putting the garment on fastens it at the top and then fastens the bottom fasteners of the chemise. If she wears a corset she then positions and fastens it under the brassière, after which she fastens the brassière; there- 55 by covering so much of the corset as is usually covered by the brassière.

By this construction the full effects are produced by my combined garment that are produced by separately constructed and sep- 60 arately handled garments, and less time is required and less material is used in the making of the combined garment than is required in the making of the separate garments.

Having described my invention I claim:

A combination under garment comprising 65 a brassière and chemise connected together at their tops, and each having an opening therein, said opening in the brassière ex- 70 tending vertically from the top to the bottom and the opening in the chemise extending vertically from the top to below the waist line when the garment is on the wearer, said openings being in register; fastening 75 means at said openings, the top fastener being common to both brassière and chemise; and shoulder straps secured to the top of the garment.

In witness that I claim the foregoing I 80 have hereunto subscribed my name this 21st day of May, 1924.

IVA CADIEUX.
